UNITED STATES PATENT OFFICE.

GEORGE L. BALL, OF ALLEGHENY, PENNSYLVANIA.

PROCESS OF REMOVING PARAFFIN FROM OIL-WELLS.

SPECIFICATION forming part of Letters Patent No. 670,577, dated March 26, 1901.

Application filed August 11, 1900. Serial No. 26,608. (No specimens.)

To all whom it may concern:

Be it known that I, GEORGE L. BALL, a resident of Allegheny, in the county of Allegheny and State of Pennsylvania, have invented a new and useful Improvement in Processes of Removing Paraffin from Oil-Well; and I do hereby declare the following to be a full, clear, and exact description thereof.

My invention relates to a process of cleaning paraffin and similar deposits from oil-wells, and has for its object a process for removing such deposits which is comparatively cheap and easy of practice and which effectively removes the paraffin or similar deposits from the side walls of the well and all parts of the well-cavity.

Oil-wells are formed by drilling or boring until a stratum of sand containing the oil or "pay-sand," as it is called, is reached and the boring or drilling continued through said stratum and for some distance into the underlying rock or slate. In some cases the flow of oil is sufficiently large without "shooting" the well; but generally after boring the well must be "shot," which is done by introducing a very heavy charge of nitroglycerin therein and exploding the same, the concussion of which forms a cavity of considerable size in the stratum of pay-sand, and the detached material is then bailed out. The cavities formed thereby are of varying sizes, depending upon the character of the soil and size of charge of nitroglycerin used, and may vary from a diameter of three or four feet to ten or fifteen feet or even more. These cavities are usually very irregular in outline, crevices or fissures extending out therefrom to a considerable extent, especially when the soil is more or less rocky. The strata of oil-bearing sands generally lie at such a depth that more or less salt water oozes into the well, and in some regions lime water is present in considerable quantities. The action of these waters upon the oil after a time causes a deposit upon the walls of the well or well-cavity, said deposit being known as "paraffin;" but it is probably, more strictly speaking, saponified oil. At any rate this deposit on the walls of the well or well-cavity after a time becomes so thick that it greatly impedes the oozing of the oil into the cavity, and it has been found necessary to either remove such deposit or

abandon the well. It has been attempted to remove this deposit in several ways. One method has been by introducing into the well 55 a rotating bar carrying at its lower end pivoted arms having on their outer ends reamers or scrapers. Said arms are projected after being introduced into the well and by the rotation of the bar are caused to ream or 60 scrape the walls of the well-cavity, thereby removing the deposit of paraffin. This method, however, is ineffective, for the reason that the sizes of the cavities vary widely and the walls thereof are so irregular that the 65 scraping-tools affect only the projecting parts thereof. It has also been attempted to heat the oil in said chamber by means of a powerful electric current to cause the same to dissolve the paraffin deposit on the walls of 70 the chamber. This method, however, has not been practical because of the excessive current necessary, the slight heating effect derived therefrom, and its decomposing action on the oil. The weight of the necessary heating coils and cables is such that in deep wells the cables will break, thereby rendering the 75 device inoperative. It has also been proposed to heat the oil by dropping hot bodies of metal into the same; but generally there is a considerable amount of oil in the well, and this, together with the long distance through which the body has to travel, cools the same to such an extent that but an ineffective amount of heat is communicated to the oil in the cavity. It 80 has also been proposed to heat the oil by introducing therein steam through a long pipe projecting down into the cavity; but in this case also the long distance through which the steam has to travel and the mass of oil through 85 which the pipe passes cool the steam sufficiently to prevent any effective amount of heat being communicated to the oil in the cavity. It has also been proposed to burn out the well by means of inflammable material introduced into the well in a tube having wooden plugs in openings in the lower end, which on striking the bottom of the well are forced out of the openings and explode a cap or similar device, which ignites the inflammable material. This method, however, 90 has never been successfully practiced.

It is the object of my invention to provide a method of removing the paraffin which

overcomes the defects of the older methods; and to this end it consists in heating the oil in the well or well-cavity by means of suitable chemicals introduced therein and when 5 the paraffin on the walls of the well or well-cavity has been dissolved then pumping or bailing out the contents of the well or well-cavity.

As is well known, the reaction of most 10 chemicals produces heat, and with certain chemicals the amount of heat produced in the reaction is very large. I avail myself of this well-known principle for generating heat in the cavities of oil-wells. The chemicals suitable for this purpose are quite numerous; but I have found by extensive experiments that ordinary sulfuric acid used with caustic soda ninety-eight per cent. pure produces the greatest amount of heat. I prefer 15 to introduce the caustic soda into the well and then introduce the sulfuric acid; but the order can of course be reversed. Three parts, by weight, of sulfuric acid to one part of caustic soda is about the proper proportion 20 when the ordinary commercial sulfuric acid and ninety-eight per cent. pure caustic soda are used; but this proportion will vary according to the strength or purity of the chemicals, which, as is well known, is never 25 uniform even in different lots from the same manufacturer. This proportion will also vary according to quality of oil in the well. For instance, if there is present in the oil a considerable quantity of lime water or salt 30 water a larger proportion of the acid will be necessary in order to neutralize the caustic soda. The well-cavity must be full of oil or the oil-bearing sand covered by oil before the chemicals are introduced, and if the oil should 35 happen to be very low it will be necessary to pour oil into the well until the cavity is full or the oil-bearing sand covered, but in most wells this is unnecessary. The reaction of 40 the acid on the alkali produces a very high degree of heat, which is communicated to the oil in the cavity and raises the same to such a temperature that it acts as a solvent for the paraffin or other deposit on the walls of the cavity or well. It usually requires about 45 three hours for the paraffin to become entirely dissolved; but this will vary, and it is necessary to test the oil in the well from time to time to determine when the paraffin is 50 dissolved. When dissolved, the contents of 55 the cavity are bailed out before the same become cool, so that the paraffin cannot again become congealed. Various acids and various alkalies may be used—as, for instance, instead of caustic soda I can use carbonate of 60 ammonia, carbonate of soda, ordinary sal-soda, or any of the ordinary alkalies, and instead of sulfuric acid I can use oxalic acid, hydrochloric acid, nitric acid, or any other well-known acid in substantially the proportions above specified in relation to sulfuric acid and caustic soda; but as sulfuric acid is 65 the cheapest common acid and as it produces

a higher degree of heat than the others in its reaction with the alkali I prefer to use the same. Turpentine, although not an alkali, in combination with nitric acid produces a very high degree of heat, in some cases bursting into flames, so that these two ingredients may be used in carrying out my process. It has also been found that in some cases the oil 70 itself has a certain amount of reaction upon the chemicals introduced in the well, so that this property may be availed of in carrying out my process.

The amount of chemicals introduced into 80 the well will depend largely upon the size of the well-cavity; but it is found that for the average well three hundred pounds of sulfuric acid and one hundred pounds of caustic soda are sufficient by their reaction to raise 85 the oil in the cavity to such a temperature that the same will act as a solvent for the paraffin. The proportions of the chemicals will be so arranged that they will practically neutralize each other, thereby preventing any injurious or harmful effect on the bailer or other apparatus necessary to use.

The chemicals may be introduced into the well by dropping or pouring them therein, and as they are heavier than the oil they sink to 95 the bottom of the well, so that the heat is generated in the cavity where it is required; but the chemicals, or at least the acids, may be put in an ordinary bailer and lowered into the well and then dumped. If preferred, all 100 of the chemicals can be lowered into the cavity by means of a bailer or other suitable apparatus.

The order in which the chemicals are introduced into the well is, as above stated, immaterial, although I prefer to first introduce the alkali and then the acid; but this order can of course be reversed, and in some cases it may be convenient or desirable to introduce them 105 simultaneously.

It will be readily apparent that my invention provides a method of removing deposits from oil-wells which is practical and effective, which is not dependent for its effectiveness upon the depth of the well or the amount of 115 oil therein, and which will reach every part of the cavity in the oil-well, no matter what the irregularities thereof may be. The cost of carrying on said process, furthermore, is 120 not excessive.

What I claim, and desire to secure by Letters Patent, is—

1. The method of removing paraffin and other deposits from oil-wells which consists in introducing into the well chemicals the reaction of which on the fluid in the well and on each other will heat the oil or fluid in the well and dissolve the paraffin or other deposits.

2. The method of removing paraffin and other deposits from oil-wells which consists in introducing into the well chemicals the reaction of which on each other will heat the oil or fluid in the well and dissolve the paraf-

in and then bailing out the well before the dissolved paraffin has cooled.

3. The method of removing paraffin and other deposits from oil-wells which consists in introducing into the well a chemical or chemicals and then introducing into the well another chemical the reaction of which with the first chemical will heat the oil or fluid in the well and dissolve the paraffin or other deposits.

4. The method of removing paraffin and other deposits from oil-wells which consists in introducing into the well an alkali and an acid in suitable proportions, the reaction of which will heat the oil or fluid in the well and dissolve the paraffin or other deposits.

5. The method of removing paraffin and

other deposits from oil-wells which consists in introducing into the well in succession an acid and an alkali in such proportions that 20 they will substantially neutralize one another and in their reaction will heat the oil or fluid in the well and dissolve the paraffin or other deposits.

6. The method of removing paraffin and 25 other deposits from oil-wells which consists in introducing into the well caustic soda and sulfuric acid in the proportions specified.

In testimony whereof I, the said GEORGE L. BALL, have hereunto set my hand.

GEORGE L. BALL.
